TICKET ISSUING MACHINE

Reuben H. Helsel, Long Island City, N. Y., assignor to General Register Corporation, New York, N. Y., a corporation of Pennsylvania

Application November 14, 1942, Serial No. 465,544

12 Claims. (Cl. 164—49)

This invention relates to a ticket issuing machine, and more particularly to the type of machine which is hand, rather than motor, actuated, though features of the invention are equally applicable to power driven machines.

Hand actuated ticket machines are in demand where there is desired a less expensive ticket issuing machine than those of power driven type or where portability, as in the case of circuses, country fairs, etc., is a necessary feature of the machine. Such machines depend for their power upon the movement of the hand, and heretofore a major objection thereto has been the amount of work necessary to accomplish a ticket issuing operation, the hand operated lever or the equivalent requiring not only the exertion of considerable force, but movement through a substantial distance. In mechanisms heretofore constructed, the expenditure of considerable energy was necessary when the tickets were to be issued with the rapidity necessary for satisfactory dispensing.

The broad object of the present invention is the provision of a machine of the hand operated type in which, as compared with the former machines, there is a minimum of work to be accomplished by the operator by reduction to a minimum not only of the force to be exerted, but of the path through which this force must be caused to act. At the same time, the machine is so designed as to issue tickets very rapidly, the number issued in a single cycle of operation depending upon the manipulation of suitable keys accompanied by only a very slight movement of light parts, so that a very light touch upon the keys is sufficient.

These general objects of the invention, together with other objects, particularly relating to details of construction and operation, will become apparent from the following description, read in conjunction with the accompanying drawings, in which:

Figure 1 is a vertical section taken immediately inside the right hand cover plate of the machine frame as viewed by the operator, the section being taken on the plane indicated at 1—1 in Figures 5 and 6;

Figure 2 is a similar section viewed in the same direction, but taken on a vertical plane to the left of an intermediate supporting plate of the frame, the section being taken on the plane indicated at 2—2 in Figures 5 and 6;

Figure 3 is a fragmentary perspective view showing certain of the elements directly associated with the ticket feed;

Figure 4 is a fragmentary vertical section taken

on the plane the trace of which is indicated at 4—4 in Figure 1;

Figure 5 is a vertical section taken on the plane the trace of which is indicated at 5—5 in Figure 1; and

Figure 6 is a vertical section taken on the plane the trace of which is indicated at 6—6 in Figure 1.

In the use of ticket issuing machines of the type of that shown in the present application, there are generally a plurality of units containing the mechanical operating parts arranged side by side in a housing or secured beneath a counter or the like. Inasmuch as such units are substantial or actual duplicates of each other and differ generally only in the ticket stock they handle, the present description will be limited to a single unit, it being understood that such unit may be removably associated with others in a suitable casing or other support. In the present instance, even more so than in the case of power driven machines, which are generally actuated by a common motor, the units are completely independent, being connected, if at all, solely by supporting strips or rods and perhaps so arranged as to be simultaneously locked.

The unit which is illustrated in the drawings comprises a frame consisting primarily of side plates 2 and an intermediate supporting plate 3, which plates are joined by various transverse members serving to hold them together and to serve as supports for such elements as the keys. The frame is, in fact, of generally conventional character heretofore used in units of this sort, the mechanism being confined as far as possible within a flat space save for those elements which must be transversely extended for the purpose of cooperation with the ticket strip or to provide the proper necessary spacing for the keys.

The selection of the number of tickets to be issued, if more than one, is to be issued in a single operation, is effected by the manipulation of keys 4, provided with downwardly extending stems 6 about which are located individual springs 8 arranged to urge the keys upwardly, the keys being guided in a transverse plate 10 and the lower ends of the stems being guided in a transverse plate 12. In the present instance, four of these keys are indicated, designed for the respective issue of two, three, four and five tickets. No manipulation of a key is necessary if one ticket is to be issued in a cycle of operation.

Each of the key stems is provided with a laterally extending pin 14 projecting through an in-

dividual vertical slot 16 formed in a member 18 and arranged to limit both the upward and downward movement of the corresponding key. On the left hand side plate of the machine there is mounted a slide 20 by the pin and slot connections indicated at 22, the slide being adapted for approximately horizontal movement and being urged to the left, as viewed in Figure 2, by the spring 24. The forward and lower edge of this slide is provided with a group of laterally extending ears 26 arranged at angles with respect to the paths of movement of the pins 14, and, as will be evident from Figure 2, adapted to be cammed by such pins as they move downwardly during the actuation of the keys. The arrangement is such that, as a key is depressed, its pin 14, by engagement with the corresponding ear 26, will cause the slide 20 to move to the right. Thereafter, upon clearing the ear, which occurs just as the pin 14 is arrested at the bottom of its slot 16, the pin will be held in lowered position by reason of the fact that the slide will move to the left under the action of spring 24, bringing the ear above the depressed pin to hold it in lowered position. The slide 20 is provided at its rear end with a turned portion 28 arranged to be engaged by a lever 31 for the purpose hereafter described.

Pivoted at 30 to the lever 31, which in turn is pivoted to the frame at 33, is a lever 32, which is provided with a series of steps 34 individually located beneath the pins 14. The rear portion of this lever, indicated at 36, is provided with a series of steps 38 of the form indicated, the successive steps being substantially angularly spaced about the center 39. A spring 40, secured at one end to the lever 32 and at the other end to the frame, serves to urge the lever in a clockwise direction as viewed in Figure 2.

A rack 42 is provided with a pin 44 extending through a slot 46 in the left hand side plate of the machine. This rack carries a laterally extending pawl 48 which, as will be described hereafter, is designed to engage selectively the steps 38. At its rear end, the rack 42 is pivoted at 50 to a link 52, the forward end of which is pivoted at 53 to a lever 54 pivoted to the frame at 56 and provided with a cam slot 58, of the form illustrated in Figure 2, within which there is located one of a pair of rollers 60 mounted on a transverse pin 62 carried by the lever 64, which is journaled upon a transverse pin 66. The rollers 60 are guided, to secure necessary rigidity, in arcuate slots 68 and 70 in the intermediate plate and the left-hand side plate 2, the rollers being duplicated merely to reduce friction inasmuch as they tend to rotate differentially. The second of these rollers operates within a cam slot 80, illustrated in Figure 2, formed in the forward arm of a lever 76 pivoted at 78 in the frame.

The lever 64, which is provided by two duplicate members, carries a transverse element 72 engageable by the fingers of the machine operator. As will be evident hereafter, the operation of the machine except for the selection of the number of tickets to be issued, is effected entirely by reason of the energy imparted by the lever 64.

The rearwardly and upwardly extending portion of the lever 76 is connected at 82 through a pivot and slot arrangement to a member 84, which is journaled upon a transverse pin 86 extending through the plate 3. To a pin 88, carried by the member 84, there is secured one end of a heavy wire spring 90, the other end of

which is secured to a member 92 through which projects a pin 94. This pin 94 extends through a clearance opening 95 in the plate 3 and on the right hand side of that plate carries a square block 96 and is secured to a lever 120, which is journaled on the pin 86, on which, as pointed out above, the member 84 is also journaled. The left hand portion of the pin 94 is arranged to engage a cam surface 104 of a lever 100, mounted upon a fixed pivot 102 and arranged at its forward end 106 to engage the rack 42 to force the latter upwardly into contact with a fixed guide 108 engaged by the rack when its teeth mesh with those of a pinion 110.

The lever 31 to which reference has heretofore been made, is connected to a lever 114 by means of a link 112, a pin 113 joining the lever 114 and link 112. This lever 114 is pivoted at 115 to the frame and carries a hook 116 engageable with the square member 96 carried by the pin 94. An ear 118 extending to the right from the lever 114 has a function which will be described hereafter.

Pivoted to the upper end of the lever 120 is a member 122 which is slotted at its forward end to embrace a movable knife 124 guided to slide in contact with a fixed knife 126, the movable knife being urged downwardly into proper shearing relationship with the fixed knife by means of a link 128 acted upon by a spring 130.

Secured to the pinion 110 is a gear 134 which meshes with a pinion 136 forming a part of a unitary assembly indicated in Figure 3. This assembly, which is journaled upon a transverse pin 138, carries a plate 140 provided with ears 142 arranged to be engageable by a detent 132 formed on an arm of the lever 120 and also by the ear 118 carried by the lever 114. A hub 144, which is also arranged to be journaled upon the pin 138, has secured to it a pinwheel 146, provided, in the instance illustrated, with five pins arranged to engage holes in a conventional perforated ticket strip. The pinwheel has mounted therein a threaded pin 147 provided with a hexagonal head 148 and arranged to be clamped in adjusted position in the pinwheel by a nut 150. The head 148 carries an eccentric pin 152 engageable within a radial slot 154 in the plate 140. By adjustment of the head 148 and the clamping of it and its associated parts in fixed position, a fine angular adjustment of the pinwheel 146 with respect to the plate 140 and the pinion 136 may be secured for the purpose of insuring the proper alignment of the tickets with the knives at the time of severance. A fine adjustment of this sort is desirable inasmuch as it is otherwise difficult to insure a sufficient accuracy of the transverse cutting of the strip between tickets.

Another pinion 155, carried by the assembly illustrated in Figure 3, serves to drive through an idler gear 156 a gear 158 secured to the shaft 160 of a counter 162 arranged to indicate the number of tickets issued.

The ticket engaging pins of the pinwheel 146 pass through a slot between ticket strip guides 153 against which the ticket strip is held by the weight of a pivoted member 157. The ticket strip is guided between the members 153 and 157 through a guide 159 suitably positioned for threading. The guiding and feeding arrangements are of conventional type.

A unit lock is provided in the form of a lever 164 pivoted to the frame at 165 and provided with a cam surface 168 arranged to engage the lower side of a pin 170 carried by the lever 31

when the locking lever is locked in a counter-clockwise direction, as viewed in Figure 1, by the operator's pulling forwardly upon the end 166 thereof.

Prior to the issue of a ticket, the parts of the machine will be in the positions illustrated in the drawings. To make clear the operation of the machine, there will be described the issue of two tickets.

The operator, in order to issue two tickets, must depress the key suitable therefor, which happens in the present instance to be that associated with the most forward key stem 6, indicated at the left of Figure 1. As the key moves down, its pin 14, by engagement with the corresponding ear 26, will push the slide 20 against the tension of spring 24 and thereafter clear the ear 26 as it reaches the lower end of its slot 16, so that the slide may be pulled back by the spring 24 to such position that the ear will overlie the pin and hold it in depressed position. As the pin reaches its lowermost position in which it is thus held, it will serve to rock the lever 32 about its pivot 30 to such extent as to locate the second step 38 on the lever 32 in the path of the projecting member 48, the corresponding step 34 engageable by the pin being so located, having regard to the radial distance from the pivot 30, that this result is accomplished. The operations so far described predetermine the issue of two tickets. It will be evident that only light weight parts are caused thus to move by the key, with the result that depression of the key requires no substantial effort.

The operator then engages the member 72 on the lever 64 and depresses the same to the extent permitted by the subsequent operations.

As will be evident from Figures 1 and 2, the initial portion of the cam groove 58 is substantially concentric with the pin 66 on which the lever 64 rocks. Accordingly, during the initial portion of the down stroke of the lever, no movement will be imparted to the lever 54.

On the other hand, the initial portion of the cam slot 80 formed in the lever 76 is substantially eccentric with respect to the pin 66, so that, during the initial movement of lever 64, the lever 76 is rocked in a clockwise direction. Through the connection at 82, this results in a counterclockwise movement of the member 84. The pin 94 is restrained from rearward movement by reason of engagement of the block 96 by the hook 116 of the detent lever 114. As a consequence, as the member 84 rocks and the pin 88 is moved rearwardly, the spring 90 is placed under additional compression which, as will be pointed out later, serves to effect actuation of the knife.

As soon as this stressing of the spring 90 is completed, the roller 60 will enter the rear portion of the cam slot 80 which, when the lever 76 is in its newly assumed position, will be substantially concentric with the pin 66 so that lever 76 is not thereafter moved, though it is locked in its position by reason of the location of the roller 60 in the cam slot. At substantially the time the roller enters this concentric portion of the cam slot 80, the other roller 60 will engage the non-concentric portion of the cam slot 58, causing the lever 54 to rock in a clockwise direction, as viewed in Figure 2. Through the link 52 there is thus imparted to the rack 42 a rearward movement. At this time, the rack will be in mesh with the pinion 110 by reason of the fact that the pin 94, occupying a forward position, will

engage the upper end of the cam surface 104 on the lever 100, which will thereby be caused to bear at 106 against the lower edge of the rack, serving to cause it to move in a path defined by the end 106 and the fixed guide 108. As the rack moves to the right, the pinwheel 146 will be rotated in a clockwise direction, as viewed in Figure 1, to effect movement of the ticket strip along the guides and through the open space between

10 the fixed and movable knives.

This uninterrupted movement of the rack continues until the pawl 48 carried by the rack engages the second tooth from the left of the group indicated at 38, formed on the lever 32, which tooth has, by reason of the key selection, been located in the pawl's path. As soon as the pawl engages this tooth, the lever 32 will be pulled to the right against the action of the spring 40 and will carry with it the lever 31 to the extent of 15 imparting a slight counterclockwise movement to this lever. Through the link 112 this counterclockwise movement is imparted to the lever 114 which, in the first part of its movement, will carry the ear 118 into the path of one of the ears 142 carried by the plate 140, to insure arresting the latter to prevent overrun, this arrest taking place after the movement of the pinwheel corresponding to the projection of the length of two tickets of the strip past the cutting plane. The further 20 movement of the lever 114 serves to raise the hook 116 out of engagement with the block 96 carried by the pin 94. Immediately, the spring 90 will snap the pin 94 rearwardly, causing rocking of the lever 120, which will first move its end 132 25 behind one of the ears 142 and then, in the same rapid motion, cause the movable knife 124 to sever the strip. It may be pointed out that these actions occur during a very small part of the movement of the lever 64, and while having a 30 definite order of succession, occur in a very small time interval, with the result that the pinwheel is brought to rest and locked therein against both forward and reverse rotation prior to the cutting stroke of the movable knife, the position of rest 35 of the pinwheel being accurately defined by two successive ears 142 located between the elements 118 and 132 acting as stops. The issue of the two tickets severed from the ticket strip is thus accomplished during the downward movement of 40 the levers 64. The downward movement of this lever is arrested at substantially the moment of tripping the lever 114 by reason of engagement of the pin 113 between the link 112 and lever 114 with the end of the slot in the plate 3 through 45 which it projects. As the lever 31 moves, it engages the ear 28 on the slide 20, moving the slide to the right so as to release the depressed key for upward movement under the action of its spring 8. By the time this release occurs, the 50 pawl 48 will have engaged the proper step, so that it is no longer necessary to have the key remain in depressed position.

The various parts are restored to initial condition upon release of the lever 64, the lever being 55 returned under the action of its spring 74, which is of sufficient strength to overcome friction. In the first part of the return movement, the lever 54 will be rocked counterclockwise, pulling with it, through the link connection 52, the rack 42. At this time, the pinwheel will remain locked 60 against rotation in both forward and reverse directions, and consequently cannot be moved by the rack. The lever 100, however, will have now been released by the pin 94 so that its left hand end 106 may rock downwardly. The teeth of the 65

pinion 110 act as cams on the teeth of the rack 42, and as a forward pull is imparted to the rack, it will be cammed downwardly, out of mesh with the teeth, rocking the lever 100 downwardly. It is found that this cam action is quite sufficient and smooth so that it is unnecessary to provide any spring for normally urging the rack 42 downwardly out of mesh. As the rack moves to the left, its pawl 48 will clear the tooth, or more generally, the teeth, 38, and the lever 32 will be restored to its clockwise position under the action of the spring 40. The action of this spring will also tend to pull the pivot 30 to the left. However, the action in this respect is limited by reason of the fact that the hook 116 will now ride upon the block 96.

At the time the roller 60 enters the concentric portion of the cam slot 58, the rack 42 will have been returned to its initial position.

At approximately the time when the roller enters the concentric portion of the slot 58, it will enter the eccentric portion of the cam slot 80, rocking the lever 76 in a counterclockwise direction. As this occurs, the member 84 will be rocked clockwise. At the time tripping occurred, the pin 94 moved to the extreme rear of the slot 98 in the member 84, exerting its residual pressure between the pin 88 and the right hand end of the slot. It will be noted, therefore, that the forces exerted by the spring merely tend to tension the member 84 between the end of the slot and the pin, but do not serve to impart any stress to move the member relative to any other part of the mechanism. It follows, therefore, that the spring 90 offers no restraint whatever to the clockwise movement of the lever 84, being merely carried thereby. As the spring 90 thus moves with the member 84, the lever 120 is rocked clockwise to retract the movable knife and also to retract its stop portion 132 from the path of the ears 142. To effect this result, the roller 60, acting in the cam slot 80, need do no more than overcome incidental friction.

As the pin 90 reaches its extreme forward position, the hook or detent 116 may drop behind the block 96, with a resulting clockwise movement of the lever 114, causing the ear 118 to clear the path of the ears 142. This action occurs due to spring 40, which simultaneously restores the lever 31 to its initial position. At the same time, slide 20 is released so as to be in position to effect key locking action. Thus, when the lever 64 reaches its uppermost position, all of the parts are restored to initial position, ready for a subsequent cycle of operation.

The operations for the issue of three, four or five tickets are essentially identical with the operation just described, with the exception that the pawl 48 will engage other teeth 38 successively more remote from its initial position, so that the rack 42 will have a stroke the length of which will depend upon the key selectively depressed and which will, in turn, effect the issue of the corresponding number of tickets prior to the arrest of the pinwheel and the cutting action.

In the case of the issue of a single ticket, it is not necessary to depress any key, but the first action may be the depression of the lever 64. As will be evident from Figure 2, in the initial position of the parts, the pawl 48 will substantially engage the most forward tooth 38. The parts are so designed that the movement imparted to the rack prior to tripping of the knife is, in this case, only sufficient to issue a single ticket.

It will be evident from the above description of the operation why the mechanism produces the issue of a ticket with a minimum exertion of work by the operator. The two operations

- 5. requiring the exertion of power are not simultaneous, but rather successive, i. e., stress is imparted to the spring 90 before the exertion of the effort to issue the desired length of ticket strip. The issuing of the strip, furthermore, is
- 10 effected directly by manual operation, and the stressing of the spring 90 need, therefore, only be such as to store up the necessary energy to effect positive actuation of the knife. The spring 74 against the tension of which the lever
- 15 64 must be moved, need only be sufficiently strong to overcome the incidental friction and weight of the parts which, in the present case, is very slight. As contrasted with prior machines, this spring or its equivalent is not required to restore any part against spring tension, the spring 90 being restored to its initial position as a unit with the member 84.

It may be noted that the pinwheel is not free to rotate during the normal non-operating condition of the machine, inasmuch as the pinion 110 is then in mesh with the rack 42, which cannot move in view of the engagement of a roller 60 in the concentric portion of the cam slot 58. It will be evident that the various leverages involved preclude any possibility of movement of the lever 64 by any forces imparted to the pinwheel 146, either through the ticket strip or otherwise.

On the other hand, short of the tripping condition, the operator may, if alert, correct a mistake in view of the fact that, upon a partial downward and then reverse movement of the lever 64, the pin wheel may be rotated first forwardly and then backwardly. On the other hand, it is impossible to project tickets in this fashion, tear them off, and then restore the parts to initial position without recording the issue of tickets on the counter, inasmuch as, upon the complete restoration of the machine, the pinwheel will lose engagement with the ticket strip. If, therefore, the locking of the ticket supply cabinet be kept under the control of a manager or supervisor, it is impossible for the machine operator to issue an unrecorded ticket without that fact's becoming noticeable.

50. The locking of the mechanism is effected as indicated by the movement of the lever 64. By such movement of the lever in a counterclockwise direction, the surface 168 is caused to move the pin 170 upwardly only to such extent as will cause the ear 118 to move in front of the adjacent ear 142 of the pinwheel, without effecting release of the pin 94. As a result of the locking of the pinwheel, it will be evident that the motion of the lever 64 will be stopped as soon as it reaches a position to move the rack 42. As a result, no further events in the cycle may occur. When the lock is released, the spring 40 will move the lever 31 sufficiently to cause the ear 118 to clear the path of movement of the ears 142.

65. It will be noted that the locking arrangement comprising the slide 20 is such that if a mistake is made in key depression, that mistake may be rectified by the depression of the correct key, inasmuch as the latter is depressed it will cause a rearward movement of the bar 20 to release the key previously depressed.

70. What I claim and desire to protect by Letters Patent is:

- 75. 1. A ticket issuing machine comprising ticket

strip guiding means, ticket strip feeding means, means for severing tickets from the strip comprising a spring arranged to effect the severing operation, and a member bodily carrying said spring but relative to which at least one extremity of said spring is movable, actuating means, and connections between the actuating means and the feeding and severing means such that, upon operation of the actuating means, said spring is first stressed so as to be in condition for effecting a severing operation, the feeding means is then actuated to feed the ticket strip, and the severing means is then caused to sever the ticket strip, said spring being thereafter carried bodily by said member during restoration of the parts to original position.

2. A ticket issuing machine comprising ticket strip guiding means, ticket strip feeding means, means for severing tickets from the strip, means for determining the number of tickets to be issued in a cycle of operation, actuating means, and connections between the actuating means and the feeding and severing means, the connections between the actuating means and the feeding means comprising a pinion and a rack for driving said pinion, said rack being releasable from said pinion, and means whereby said rack effects operation of the severing means at the completion of the feeding of the predetermined number of tickets.

3. A ticket issuing machine comprising ticket strip guiding means, ticket strip feeding means, means for severing tickets from the strip, means for determining the number of tickets to be issued in a cycle of operation, actuating means, and connections between the actuating means and the feeding and severing means, the connections between the actuating means and the feeding means comprising a pinion and a rack for driving said pinion, said rack being releasable from said pinion, and means whereby said rack effects operation of the severing means at the completion of the feeding of the predetermined number of tickets, and simultaneously effects its release from said pinion.

4. A ticket issuing machine comprising ticket strip guiding means, ticket strip feeding means, means for determining the number of tickets to be issued in a cycle of operation, actuating means, and connections between the actuating means and the feeding and severing means, the connections between the actuating means and the feeding means comprising a pinion and a rack for driving said pinion in opposite directions during meshing thereof, said rack being releasable from said pinion, and means whereby said rack effects its release from said pinion at the completion of the feeding of the predetermined number of tickets.

5. A ticket issuing machine comprising ticket strip guiding means, and ticket strip feeding means comprising a pinwheel for engaging openings in a ticket strip and an actuating member therefor, and means for adjusting the position of the pinwheel relative to said actuating member, the last named means comprising an eccentric pin and slot connection between the pinwheel and member.

6. A ticket issuing machine comprising ticket strip guiding means, ticket strip feeding means, means for severing tickets from the strip, oscillatory, manually operable actuating means having forward and reverse strokes in the complete cycle of operation of the machine, and connections between the actuating means and the feed-

ing and severing means such that, during operation of the actuating means in its forward stroke the severing means is first placed in condition for operating, the feeding means is thereafter positively advanced to an extent depending upon the extent of movement of the actuating means to feed the ticket strip, and at substantially the end of movement of the actuating means in its forward stroke the severing means is caused to sever the ticket strip.

7. A ticket issuing machine comprising ticket strip guiding means, ticket strip feeding means, means for severing tickets from the strip, oscillatory, manually operable actuating means having forward and reverse strokes in the complete cycle of operation of the machine, means for predetermining the extent of the forward stroke of the actuating means, and connections between the actuating means and the feeding and severing means such that, during operation of the actuating means in its forward stroke the severing means is first placed in condition for operating, the feeding means is thereafter positively advanced to an extent depending upon the extent of movement of the actuating means to feed the ticket strip as determined by said predetermining means, and at substantially the end of movement of the actuating means in its forward stroke the severing means is caused to sever the ticket strip.

8. A ticket issuing machine comprising ticket strip guiding means, ticket strip feeding means, means for severing tickets from the strip comprising a spring arranged to effect the severing operation, oscillatory, manually operable actuating means having forward and reverse strokes in the complete cycle of operation of the machine, and connections between the actuating means and the feeding and severing means such that, during operation of the actuating means in its forward stroke the severing means is first placed in condition for operating by stressing said spring, the feeding means is thereafter positively advanced to an extent depending upon the extent of movement of the actuating means to feed the ticket strip, and at substantially the end of movement of the actuating means in its forward stroke the severing means is caused to sever the ticket strip.

9. A ticket issuing machine comprising ticket strip guiding means, ticket strip feeding means, means for severing tickets from the strip comprising a spring arranged to effect the severing operation, oscillatory, manually operable actuating means having forward and reverse strokes in the complete cycle of operation of the machine, means for predetermining the extent of the forward stroke of the actuating means, and connections between the actuating means and the feeding and severing means such that, during operation of the actuating means in its forward stroke the severing means is first placed in condition for operating by stressing said spring, the feeding means is thereafter positively advanced to an extent depending upon the extent of movement of the actuating means to feed the ticket strip as determined by said predetermining means, and at substantially the end of movement of the actuating means in its forward stroke the severing means is caused to sever the ticket strip.

10. A ticket issuing machine comprising ticket strip guiding means, ticket strip feeding means, means for severing tickets from the strip, actuating means having forward and reverse strokes in the complete cycle of operation of the ma-

chine, and connections between the actuating means and the feeding and severing means such that, during operation of the actuating means in its forward stroke the severing means is first placed in condition for operating, the feeding means is thereafter positively advanced to an extent depending upon the extent of movement of the actuating means to feed the ticket strip, and at substantially the end of movement of the actuating means in its forward stroke the severing means is caused to sever the ticket strip, said connections comprising a plurality of successively operating cam devices for effecting said succession of operations.

11. A ticket issuing machine comprising ticket strip guiding means, ticket strip feeding means, means for severing tickets from the strip comprising a spring arranged to effect the severing operation, actuating means having forward and reverse strokes in the complete cycle of operation of the machine, and connections between the actuating means and the feeding and severing means such that, during operation of the actuating means in its forward stroke the severing means is first placed in condition for operating by stressing said spring, the feeding means is thereafter positively advanced to an extent depending upon the extent of movement of the ac-

tuating means to feed the ticket strip, and at substantially the end of movement of the actuating means in its forward stroke the severing means is caused to sever the ticket strip, said connections comprising a plurality of successively operating cam devices for effecting said succession of operations.

12. A ticket issuing machine comprising ticket strip guiding means, ticket strip feeding means, means for locking said feeding means to prevent movement of the ticket strip, means for severing tickets from the strip, actuating means having forward and reverse strokes in the complete cycle of operation of the machine, and connections between the actuating means and the feeding and severing means such that, during operation of the actuating means in its forward stroke the severing means is first placed in condition for operating, the feeding means is thereafter positively advanced to an extent depending upon the extent of movement of the actuating means to feed the ticket strip, said locking means is rendered effective, and at substantially the end of movement of the actuating means in its forward stroke the severing means is caused to sever the ticket strip.
